UNITED STATES PATENT OFFICE.

BALDWIN G. WHITFIELD, OF CHICAGO, ILLINOIS.

CIGARETTE-PACKAGE.

1,294,584.

Specification of Letters Patent. Patented Feb. 18, 1919.

Application filed July 25, 1918. Serial No. 246,675.

To all whom it may concern:

Be it known that I, BALDWIN G. WHITFIELD, a citizen of the United States, residing at Chicago, in the county of Cook and State of Illinois, have invented new and useful Improvements in Cigarette-Packages, of which the following is a specification.

This invention relates to paper and other receptacles employed for holding cigarettes, and its object is to provide a novel and improved receptacle from which the cigarettes may be ejected singly, thus doing away with the annoyance and trouble of removing cigarettes from the ordinary containers, and which usually render it difficult to reach thereto without damaging some of the cigarettes. The present device provides a container having a lid which draws out one cigarette each time it is opened, leaving the others untouched and in their proper shape.

The object stated is attained by means of a combination and arrangement of parts to be hereinafter described and claimed, and in order that the same may be better understood, reference is had to the accompanying drawing forming a part of this specification.

In the drawing,

Figure 1 is a longitudinal section of the device;

Fig. 2 is a cross section thereof, and Fig. 3 is a detail in perspective.

Referring specifically to the drawings, the container for the cigarettes 5 is rectangular, and has side walls, 6 and 6^a, respectively, and walls 7 and 7^a, respectively, a bottom cap 8 and a top wall 9. These parts are made of pasteboard, paper or other suitable material and they are connected in the usual manner. The container is dimensioned to hold three rows of cigarettes.

Over the top wall 9 is fitted a cover flap 10 hinged thereto by a tape 11, or by any other suitable means. This flap covers an opening 12 in the wall 9 adjacent to the end wall 7, through which opening the cigarettes are adapted to be ejected singly in a manner to be presently described, the opening being of a size to accommodate one cigarette at a time.

Close to the end wall 7, inside the container, slidably seats an ejector composed of two thin flexible strips 13 connected at their outer ends to the flap 10 near the free end thereof. These strips are parallel and laterally spaced, and at their inner ends they have a connecting piece which is bent down-

wardly, as shown at 15, and formed with two forwardly extending tongues 16 which are laterally spaced the same as the strips 13 and lie beneath the latter. The space 60 between the strips 13 and the tongues 16 is in line with the opening 12 and forms a pocket to hold a cigarette, so that when the ejector is advanced by swinging the flap 10 outward to uncover the opening 12, the 65 cigarette so held is ejected through the opening as shown dotted in Fig. 1, so that it may now be easily taken hold of and removed from the container. It will be noted that the wall 9 stops short of the wall 70 so that the strips 13 may pass to the flap 10.

As shown in Fig. 2 the thickness of the container only accommodates three rows of cigarettes, and of the three bottom cigarettes, the outer two will rest on the strips 75 13, whereas the middle one rests on the wall 7, in the space between the strips 13 and the tongues 16, and at a lower level than the end ones. Hence when the flap 10 is drawn, the middle cigarette will be ejected as described, 80 and when it is withdrawn, and the flap is closed to push the ejector back into the container, another cigarette rolls into the place of the one which was removed, a slight jar-ring of the container facilitating this.

The container will be filled before the bottom cap 8 is applied and secured, and the container is not designed for refilling.

The container may be made of sheet metal for permanence and greater rigidity, and a 90 spring device may be provided for automatically opening the flap 10 outward. Such spring-actuated lids or covers being well known, a detailed description or an illustration thereof not deemed necessary.

I claim:

1. A container having a discharge opening, a hinged flap covering the opening, and an ejector slidably mounted in the container and connected to the flap, said ejector having a pocket in line with the discharge opening, and portions alongside the pocket to support the articles which are alongside the one being ejected.

2. A container having a discharge opening, a hinged flap covering the opening, and an ejector slidably mounted in the container, said ejector being composed of a pair of laterally spaced strips connected at their outer ends to the flap and having at their inner 110 ends a downturned connecting member, the space between the strips being in line with

the aforesaid discharge opening, and having a width to receive the article to be ejected, the strips supporting the articles which are alongside the one being ejected.

- 5 3. A container having a discharge opening, a hinged flap covering the opening, and an ejector slidably mounted in the container, said ejector being composed of a pair of laterally spaced strips connected at their outer ends to the flap and having at their inner ends a downturned connecting member pro-

vided with forwardly extending laterally spaced tongues located beneath the strips, the space between the strips and the tongues being in line with the aforesaid discharge 15 opening, and having a width to receive the article to be ejected, the strips supporting the articles which are alongside the one being ejected.

In testimony whereof I affix my signature. 20

BALDWIN G. WHITFIELD.
